1974, Ser. No. 435,764

Term of patent 14 years
The term of this patent subsequent to Sept. 3, 1991,
has been disclaimed

Int. Cl. D11—01

U.S. Cl. D45—1 B

FIG. 1

FIG. 2

FIG. 3

FIG. 1 is a perspective view taken obliquely from above of a mount for precious stones showing my new design;

FIG. 2 is a perspective view taken obliquely from below; and

FIG. 3 is a top plan view.

This application is a continuation-in-part application of U.S. design application Ser. No. 290,855, filed Sept. 21, 1972, and entitled "A Mount for Precious Stones."

I claim:

The ornamental design for a mount for precious stones, as shown and described.
